[57] **CLAIM**

The ornamental design for heat circulating fireplace system for use in masonry construction, substantially as shown and described.

DESCRIPTION

FIG. 1 is a front perspective view of a heat circulating fireplace system for the use in masonry construction, showing our new design;

FIG. 2 is a front elevational view thereof;

FIG. 3 is a right side elevational view thereof, the left

side being a mirror image thereof;

FIG. 4 is a top plan view thereof.

FIG. 1

FIG. 2

FIG. 3

FIG. 4
